UNITED STATES PATENT OFFICE

123,479

DESIGN FOR A CASE FOR CLOCKS OR SIMILAR ARTICLES

Frederick E. Greene, Westport, Conn., assignor to
The Sessions Clock Company, Forestville, Conn.,
a corporation of Connecticut

Application May 9, 1940, Serial No. 92,241

Term of patent 14 years

To all whom it may concern:

Be it known that I, Frederick E. Greene, a citizen of the United States, residing at Westport, in the county of Fairfield and State of Connecticut, have invented a new, original, and ornamental Design for a Case for Clocks or Similar Articles, of which the following is a specification, reference being had to the accompanying drawing, forming part thereof.

Fig. 1 is a face view of a case for clocks or similar articles showing my new design; and
Fig. 2 is a view thereof in edge elevation.

I claim:

The ornamental design for a case for clocks or similar articles, substantially as shown.

FREDERICK E. GREENE.
